GARMENT AIR STEAM FINISHER

August F. Paris, Oak St., Brockway, Pa.

Filed Feb. 27, 1956, Ser. No. 568,024

7 Claims. (Cl. 223—67)

This invention pertains to apparatus or equipment for renovating, shaping, pressing, and finishing clothing or garments. It is of a type that may make use of a porous or permeable bag of an inflatable material of a suitable somewhat flexible fabric such as nylon, etc.

In a machine employing a fabric bag such as contemplated in the present disclosure, the bag has an open bottom portion or edge that is secured in position at a base portion of the apparatus from which steam and heated air are introduced upwardly to inflate it to a proper shape or form for the garments to be processed. The bag, as employed, defines a chamber that is, for the most part, closed off so that air and dry steam may be forced through its porous walls to simultaneously condition, shape and press a garment mounted on the bag. That is, in accordance with the contemplated procedure, a garment is positioned over the bag and is directly or indirectly subjected to inflation during the conditioning and pressing operation.

In a co-pending application entitled "Base and Heating Unit," Serial No. 567,996, filed February 27, 1956, now Patent No. 2,915,229, granted December 1, 1959, I have shown a suitable base construction that may be employed with the shaping apparatus of this application. The present disclosure relates particularly to upright standard and associate equipment to be employed with a bag in accomplishing pressing and finishing operations.

An object of my present invention has been to devise improved equipment for conditioning garments and particularly, an improved upright structure for such a purpose;

Another object has been to devise equipment for garment conditioning and pressing that will be adaptable to various types of garments, including dress and sport shirts, sweaters, jackets, dresses, blouses, overcoats, suit coats, etc., and whether such garments are of natural, vegetable or animal fibres, are of synthetic materials, or are of a mixture of materials;

A further object has been to provide for the shaping of different types of collars for shirts, including sport shirts;

A still further object has been to provide improved procedure for conditioning and shaping clothing by means of a flexible-inflatable application of steam and air and to substantially all areas of the clothing;

These and many other objects of my invention will appear to those skilled in the art from herein illustrated features thereof.

In the drawings, Figure 1 is a front view in elevation of a complete pressing and finishing unit constructed in accordance with my invention. In this view, right and left-hand sleeve clamps are illustrated with one of them in an open position and the other in a closed position; a front pressing clamp for front edges of the garment is also illustrated;

Figure 1A is a somewhat fragmental side elevation on the same scale as and taken at right angles to Figure 1; in this figure, the central cone-shaped structure for

2

dresses, overcoats, etc., of Figure 1 has been removed to illustrate the mounting of a central support member or column of the apparatus; in addition, a slightly modified type of upper end construction is shown;

5 Figure 2 is an enlarged side view in elevation of the sleeve clamp shown in Figure 1 and with the members in an open or sleeve-receiving position;

Figure 3 is a front view in elevation on the same scale as and of the clamp apparatus of Figure 2;

10 Figure 4 is a section through an adjustable joint provided for the sleeve holder of Figures 2 and 3 which makes use of pivotally mounted concentric cylindrical joint members provided with a series of holes for receiving a locking pin in a number of positions therethrough;

Figure 5 is a side elevation on a slightly enlarged scale of the front pressing clamp shown in Figure 1;

Figure 6 is a section taken along the line VI—VI of Figure 5 showing a clamping-down plunger with a single clothing engaging clamping surface;

20 Figure 7 is a view similar to Figure 6 of a fragment of a modified construction in which dual flaps or clamping surfaces are provided;

Figure 8 is a side view in elevation on the scale of Figures 5, 6 and 7, illustrating a modified front pressing clamp construction having a collar finisher mounted at its upper end;

Figure 9 is a front view in elevation of a clamping construction suitable for a flap of a long or heavy garment such as a man's overcoat;

30 Figure 10 is a side view in elevation showing the clamp of Figure 9 in an open position;

Figure 11 is a horizontal section taken along the line XI—XI of Figure 9;

35 Figure 12 is a side view in elevation of the scale of Figures 6, 7 and 8 of a sleeve clamp holder; the full lines represent it in its normal clamping relationship and the dot and dash lines represent it in a flexed or opened relationship;

Figure 13 is a top plan view of the construction of Figure 12;

40 Figure 14 is a front view in elevation illustrating an adaptable part which may be used with the apparatus of my invention for expanding and forming sleeves;

Figure 15 is a fragmental and somewhat diagrammatic side view showing another adaptable means which may be used with an inflatable garment bag having attached and inflatable sleeve portions which may be supported and engaged at their cuff ends by the means of this figure;

45 Figure 16 is an enlarged fragmental front view in elevation of a breastplate, shoulder and collar support form such as employed in the construction of Figure 1;

50 Figure 17 is a back view of the structure of Figure 16 illustrating heating coils that are positioned along the breastplate; in this figure, the flow holes or ports in the breastplate have been omitted;

55 Figure 18 is a vertical section taken along the line XVIII—XVIII of Figure 17;

Figure 19 is a horizontal section taken along the line XIX—XIX of Figure 17 and showing a shoulder expander in its fully closed position;

60 Figure 20 is a horizontal section taken along the same lines as Figure 19 and showing the shoulder expander in a maximum open position;

65 Figure 21 is a top view of the breastplate with a collar attachment in position with a collar cup or cap to provide a shirt collar of one form of shape;

Figure 22 is a rear view in elevation of the structure of Figure 21 and Figure 23 is a vertical section along the line XXIII—XXIII of Figure 21;

70 Figure 24 is a fragmental front view in elevation on the scale of Figures 21 to 23 and illustrating another form of replaceable collar finishing attachment;

Figure 25 is a section in elevation taken along the line XXV—XXV of Figure 24;

Figure 26 is a top plan view of a third type of collar finisher attachment and Figure 27 is a section in elevation taken along the line XXVII—XXVII of Figure 26;

Figure 28 is a reduced view in elevation of the back portion of an expander bag of my invention and Figure 29 is a side view of the construction of Figure 28 showing it in a mounted relationship on a base stand or unit;

Figure 30 is a bottom view looking up along the form of Figure 28 showing it with a coat in position thereon; this is a fragment for the purpose of clarity;

Figure 31 is also a somewhat fragmental view taken in the direction of the line XXXI—XXXI of Figure 29 and showing how support rods for the form are carried by a base rim 25.

Although for the purposes of simplicity in illustrating the frame or form structure of my present invention I have not shown the nylon bags, it may be noted that the apparatus is adapted to make use of any conventional type of bag or any improved type of bag, including bags having open as well as closed collar cap ends, those having connecting and inflatable sleeves, and those terminating at the arm pits and being open thereat to supply the fluid directly, if desired, to arm portions of a garment. I also contemplate the use of so-called slide fasteners in adapting an inflatable bag or form to various sizes of garments; in this connection, I may use a slide fastener in an edge closing relationship to take in excessive material lengthwise along the body of the bag and separate the fastener when a larger body is required.

Referring particularly to Figure 1 of the drawings, I have devised a unit 10 that may be used as a fixed unit in a clothing factory production line or may be used as a master unit with interchangeable parts for adapting it to the requirements of different types of garments in a cleaning and pressing shop. In the unit 10 illustrated in Figure 1, A generally represents a base and heating unit, such as disclosed in said co-pending application Serial No. 567,996; B represents an upright support frame structure, C represents suitable means for holding extended and for processing or pressing sleeve portions of a garment, D represents a front presser clamp for front edges of the garment (as shown in Figure 8) and which may also be used for shaping the collars of the garments, E represents an adaptable shoulder support or expander which is mounted on the column structure and is adjustable for different sizes and types of garment shoulders, and F represents a clamping means for a rear portion of a garment, such as its flap or tail portion. Generally speaking, I contemplate mounting the sleeve and cuff processing means or equipment on a bottom portion of the base of the heating unit A and to mount edge and collar finishing and flap clamping and handling means on an upper flange portion of the heating unit.

In Figure 1, the heating unit A as shown in Figures 4, 5 and 7 of my Patent 2,417,838, is of metal construction and includes therein a heating coil system for heating air and a motor-driven circulating fan positioned or enclosed within the cylindrical portion 11. Processing air is drawn-in through a grillwork 12 which is reinforced by flanges 13 and 15 and by vertical ribs 16. Also, a so-called centrally located steam supply unit 26 projects upwardly within and above the enclosure 11 to, as shown in Figure 1A, support a central column or tubular upright standard member 27 within its bore 26a. As shown, this bore carries a ball for the end of the rod and vertically spaced bearing portions 26b to rotatably mount the column 27. Also, as shown in Figure 1A, warm air is adapted to rise from the heating unit in the base A as indicated by the arrows a, and steam flows from the steamer 26 as indicated by the arrows b.

The equipment C is, as particularly shown in Figures 1, 2 and 3, adapted to be positioned on mounts car-

ried by the bottom portion of the heating unit A. In this connection, a mounting plate 18 is secured as by weld metal to connecting member 17 and reinforcing rib members 16, Figure 1. A bottom flange of an angle ring 13 is also secured to the mounting plate 18. On the other hand, an upper assembly 20 consisting of a rim and a flange and a reinforcing piece 19 is used for mounting flap clamps as well as edge and collar finishing clamp means.

As noted particularly in Figure 1A, the flange forming a part of assembly 20 is a part of the stationary base unit A. A circular wheel or rim member 25 (Figures 1 and 1A) is mounted for engagement within an inside circular track of the rim and flange assembly 20 and is rotatable with respect thereto. Spokes projecting from the inside of the wheel or circular rim 25 mount and carry the steamer unit 26 as suspended therefrom within the heating zone of the unit A. The unit 26 is open or has a grating at its top end to discharge steam, as indicated by arrows b, into a garment bag. If desired, the column 27 may be reinforced by diagonal braces or spokes 24 which are secured at one end thereto and at their other ends to the wheel 25. If the upper support structure is relatively lightweight, the tie members 24 may be eliminated; in such an event the column 27 may be freely rotated with respect to the steamer 26 and also with respect to the wheel 25.

Referring particularly to Figures 16, 17 and 18, the upper end of the column 27 is shown secured as by weld metal w to a U-shape support bracket 28 (Figure 17). The bracket has mounting feet 28a which may be secured, as shown in Figure 17, to project downwardly from the bottom side of a shoulder support part 30. As also shown in Figure 18, the shoulder part is substantially enclosed by a metal casing made up of a collar cap part 32 and a breastplate part 33. The collar or cap part 32 has a rounded front face 32a, see Figures 16 and 18. A top wall portion 32c slopes backwardly to provide a latching edge 32d and is connected to a substantially plane vertical back wall 32b. The breastplate 33 has a back shoulder portion 33a that defines an open slot 33b with the back wall 32b of the cap. As shown, for example, in Figures 21 to 27, inclusive, the back wall 32b carries a guide pin 31 projecting backwardly therefrom for guiding one of a series of collar adapter elements into position, see particularly Figure 22.

The breastplate member 33 has a series of ports or openings 33c therethrough to permit the discharge of air and steam upon the surrounding inflatable bag and, in turn, through it into the garment. The breastplate member 33 is heated by means of a steam heating coil system consisting of up-flow line 45 and down-flow line 46. As utilized, the end portion 45a of the coil is connected to the up-flow steam lines of the unit A and the outlet portion 46a is connected to an outlet line of the same unit.

Referring particularly to Figures 18, 19 and 20, the shoulder expander unit E has a central support part 35 made up of a series of interconnected parts that are secured together by some suitable means, such as set screws 35a. A vertical adjustment shaft 36 is operatively mounted to extend at its lower end within the part 35 and is keyed, as shown, to a pinion 37 for operating a pair of racks 44 and 44'. As shown particularly in Figure 18, the shaft 36 projects upwardly through an opening or bore in the shoulder part 30a and is journaled therein by bearings 38a and 38b. The pinion 37 has a bearing and spacer piece 38 between it and the lower bearing 38a. The shaft 36 is supported in the assembly by a collar 38c which is secured as by a set screw or pin to the shaft to rest on the upper bearing 38b and support the shaft 36. The shaft extends upwardly through a hole in the top portion 32c of the cap 32 and has an operating lever 39 secured thereto by pin 36a. It is thus apparent that a rotation of the lever 39 will rotate the pinion 37 and in

turn, move the shoulder expander to various positions as shown in Figures 19 and 20.

Referring again to Figures 17-20, the unit E is supported on oppositely disposed brackets 40 which are spaced one from the other and are secured to the shoulder part 30. Slide apertures 40a are provided in one bracket 40 to slidably engage telescopic members 41 and 43 of the expander unit E and the other bracket is provided with spaced slide apertures 40b, each of which receives one of the telescopic members 41' and 43'. A male and female slide part, such as 41 and 43, is secured to a cross connecting and rounded shoulder support member 42 and in the case of the members 41' and 43', by the part 42'. Racks 44 and 44' are actuated by a pinion 37. It is thus apparent that when the pinion 37 is rotated, that the telescopic parts expand and contract to conform to the particular type or size of garment being supported. If desired, graduations may be placed on the top portion 32c of the cap 32 to indicate proper adjustments for certain sizes of garments.

As shown in Figure 1, the breastplate member 33 may, if desired, be supplemented by an interfitting vertical plate member 34 having ports 34a therethrough. This member may extend in an inclined relationship from the breastplate member 33 to, at its other end, be secured on the wheel or circular rim 25. The assembly may be reinforced by cross brace or bolts 23, as indicated in Figure 1A, which extend to the center column 27.

In Figures 1 and 5, I have illustrated a form of front edge pressing and clamping cover plate assembly. As shown, the assembly is secured as by welding to a reinforcing mounting piece 19 which is secured to the cylindrical shell 11 adjacent the rim assembly 20 of the unit A. The front assembly includes a bifurcated angle bracket 55 which has a lower cross pin 57 extending through its fork portions or bifurcations to pivotally engage opposed ear portions 56a (Figure 5) of a cover channel member 56. An upper cross pin 58 (Figures 1 and 5) reinforces the fork portions of bracket 55 and provides a stop which limits the swing of the channel member 56 toward the surface of the conical members 50-51. The channel member 56 is normally urged towards an in-swing position by a tension spring 59. The spring, as shown particularly in Figure 5, is connected at one end by a pin 60a to the mounting bracket 55 and at its upper or other end by a pin 60b to the member 56.

A pair of strap-like side members 61 are secured, as shown in Figure 1, by bolt assemblies 62a and 62b to side flanges of the channel members 56 to extend therealong and slidably receive suitable garment pressing and stretching means shown in Figures 5, 6, and 7. A series of spaced apertures 61a is provided along each of the members 61 so that the means may be secured in an adjusted relationship and cooperate with set screws, such as 81 of Figure 6. A handle 65 (Figures 1, 5, and 8) is secured to the upper end of the member 56 to move the clamping assembly into and out of a pressing and cooperating relationship with the garment and generally in the direction of the line 50, 51 of Figure 5.

A front edge presser member 66 having a presser face 66a is carried by a pair of mounts 67 which are connected at one of two positions 67a and 67b to a mounting finger 68. Each mounting finger 68 is secured on a separate rectangular slide sleeve 69 corresponding to the sleeves 80 of Figure 6. Set screws 81 hold them in position with respect to the side members 61.

In Figure 5 and below the pressing plate 66, I have shown an adjustable clothing stretcher or tensioning device 70 which is also adapted to slide along members 61 and to be positioned in one or another of a number of apertures 61a along these members. An arm 71 projects along one side of the device 70 and has a counter-weighted end 72. Its other end is secured as by bolt and nut assemblies 74 to an angle piece 73. The piece 73 carries a suitable backing piece 75, a pad 77 and an abrasive sur-

face such as 77a. The assembly which includes the backing member 75 is secured in position by screws 76.

A support member 78 projects from the L-shaped angle piece 73 shown in both Figures 6 and 7, and carries a forked or yoke shaped member 79, each end of which carries a rectangular slide member 80. A separate one of the two strap members 61 passes through each slide member 80. A set screw 81 is carried by the arm 71 and is adapted to extend into and through an aperture formed in one of the slide members 80 and into one of the apertures 61a of the proximal strap member 61, to thereby lock the tensioning device 70 in adjusted positions along the channel 56. In this way, the device 70 may be slid up and down and, as employed, will engage the front of the clothing ahead of the presser 66 and as the in-swing movement is continued, will by reason of its abrasive surface 77a, tend to force the front portion of the fabric downwardly and stretch and align it to receive the presser plate 66.

In the embodiment of Figure 7, the L-shaped angle piece 73 for mounting the pressure block construction carries a pair of backing pieces 75', a pair of fabric pieces 77', having an approximation of a carding surface 77'a. The surfaces 77'a are employed instead of the abrasive surface 77a for heavier clothing, such as men's woolen coats, while the abrasive surface or traction cloth 77a may be used for more delicate clothing, such as women's clothing. The principle of operation is the same in both cases in that the purpose is to stretch the front of the garment before the front presser plate comes into engagement therewith. As to Figure 7, so-called weaver's carding pad surface or wire carding brush 77'a with its fine needle-like bristles or splines pointed or inclining downwardly has been successfully used for the abrasive surface 77'a.

In Figure 8 of the drawings, I have shown a modified and simplified form of front presser clamp D'. In this form, the parts which are the same as those of the embodiment of Figure 5 have been given the same numerals, while those parts which are slightly modified or adapted have been given prime suffixes. The front channel member 56' has a handle 65 secured thereto. A backing plate 82 is pivotally secured to the member 56' by a bolt 83. The plate 82 carries a pressing plate 84. A mount 86 for a collar presser and finisher is secured to the rear face of the plate 84 at its upper end. The collar presser includes a plate support 87 pivotally secured to the mount 86 by a pivot pin 88. The support 87 carries at its free end a presser plate 90 and is also provided with an operating handle 89 for swinging the plate 90 to different positions about the pin 88.

In Figures 1, 2 and 3 I have shown a sleeve and cuff presser or finisher C. This finisher is mounted for swing or pivot movement about the mounting bracket 18 by its mounting plate 92, somewhat flexibly between the bracket 18 and vertically extending telescopic members 96 and 100, and is further adjustable pivotally mounted between its telescopic members and its inner support, see particularly Figures 2 and 4. More particularly, mounting plate 92 is pivotally secured on the angle shaped bracket 18 by a pivot bolt 93. It also has a clamping bolt 94 which, when loosened, may be moved along slot 92a to move the plate 92 in a pivotal relationship about 93. The plate 92 may be then locked in such relationship by tightening the bolt 94. A male telescopic member 96 has a flattened lower end portion which is secured by bolt and nut assembly 97 to a projecting flange portion 95 of the plate 92 (Figure 2). To provide some flexibility yet stability in the mounting an additional bolt and nut assembly 98 is employed which carries a compression spring to give it flexibility.

A vertically extending female or outer telescopic support tube or member 100 slidably receives the inner member 96. The members 96 and 100 are movable with respect to each other to adjust the vertical operating height

of the unit C so that it may be employed for garments having long as well as short sleeves. The outer member 100 carries a locking clamp screw 101 which may be turned to loosen and tighten it with respect to the member 96 to in this manner adjust the members with respect to each other and, when adjusted, to securely hold them in such a relationship.

As shown particularly in Figures 2 and 4, the upper end of the outer sleeve member 100 has a short length cylinder or collar 102a secured thereto as by welding. The outer collar or sleeve 102a is adapted to receive therein a smaller or inner sleeve 102b. The latter is secured at its end to and is carried by a back mount or stand 103 whose base portion 103a is secured by screws 104 to a rib portion 106 of a presser plate member 107. The interfitting sleeves 102a and b have, as shown in Figure 4, a series of holes that may be aligned with each other to provide a desired tilted relationship between the mounting stand 103 and the outer support member 100. Such members are retained in the desired tilted relationship by a pin 105 that may, as shown in Figure 2, be suspended by a wire from the stand 103.

The back clamping or presser plate 107 carries a curved plate 109 which serves as a deflection plate to contact the sleeves of the garment to be pressed. In addition, a pair of spreader bars or rods 111 and 114 are mounted on the inner side of the plate 107. The bar 111 is secured by means 112 to project upwardly along one side of the plate 107. The slightly curved means 114 is secured at its lower end 115 to the plate 107 and is adjustable as to its flexible positioning by a spring means 118. It will be noted that the spring is secured at one end 118a to the expander rod 114 and at its other end to a turn buckle or spring pin 119. The tension of the spring 118 is adjusted by a thumb screw 120. It will be noted that the spring pin 119 is mounted at one end of a support bracket 116 which projects from the back side of the plate 107. A strap clamp 113 is secured by means 113a on the inside of the plate member 107 to confine the lower end portion of the spreader rod 114. As shown by the dot lines, this spreader rod 114 is movable sideways within strap clamp 113 and is controlled by the spring 118 and its pin 119. In carrying out a pressing operation the bar 111 and rod 114 may be inserted within the cuff or sleeve to form a crease and keep the cuff or sleeve spread while the clamping plates are closed upon the cuff or sleeve.

The clamping assembly which includes the pressure plate 107 also includes a cooperating channel-shaped clamp part 122 which is provided on its lateral edges and at or adjacent its lower end with a pair of spaced ears 122a. Each of these ears is pivotally secured to one of a similar pair of ears 107a formed on the clamp part 107. A separate pivot pin 121 forms a means of connection between each ear 107a and a separate one of the ears 122a. Tension springs 123, shown in Figures 2 and 3, are located on opposite sides of the clamp part 122. One end of one such spring is shown as secured to the clamp part 122 and the other end thereof is shown in Figure 2 as secured to one of the so-called ears 107a which, as noted, is formed on the clamping part 107. A curved member 126a is pivotally secured to the part 122 by a pin 126b. One free end of the member 126a bears against the plate 107 whereas the other end is provided with a handle portion 126. Lifting the handle portion causes the opposite end of the member 126a to move downwardly along the clamp part 107 and to a point below the pivot pin 121 and out of contact with part 107, thus permitting the opposed clamping parts of the clamp assembly to move into clamping engagement and impose finishing pressure on the lower end of a garment sleeve which is engaged by the bar 111 and the spring impelled rod 114. The pressure plate 124 is provided on its rear face with an elongated rectangular rib which fits into the open channel face of the clamp part 122 and is pivotally secured there-

to by a pin 125. If desired, a face plate 109a may be positioned on and secured to the plate 124. In operation the plate 109a cooperates with a similar plate 109 on the clamp part 107 in the pressing of a sleeve of a garment being processed on the pressing machine. As shown, the upper end of each of the plates 109 and 109a may be formed so that they are curved outwardly with relation to each other.

If air and steam are to be directly supplied to the inside of the sleeves or arms of the garment that is to be pressed through open arm pits of the nylon bag or shaping form, then the clamping mechanism C of Figures 2 and 3 will serve to close off the cuffs or ends of the sleeves as well as to press them. As intimated before, the sleeve or cuff expander elements 111 and 114 are first entered before the opposed plate members are closed or are clamped together.

In Figures 12, 13, 14 and 15 I have shown other adaptable means which may be used with a presser construction of my invention to adaptably meet the requirements for various types of clothing as well as somewhat varied types of procedure. In Figure 12 I have shown a swingable and adjustable support rod construction similar to that described in connection with figures 3 and 4, except that the lower member 130 is now the female member to receive the upper member 131 which is now a male member. The lower end 130a of the member 130 is flattened for mounting it on the right angle flange 95 of the mounting plate 92. The lower end portion of the inner and upper vertical support member 131 has spring-like fingers 132, as shown in Figure 12, and if desired, a locking or clamping swing nut 101 similar to the nut of the same number of Figures 2 and 3. The spring 132 acts as an entry guide when the two members 130 and 131 are assembled and to also add stability to the adjustment of the members 130 and 131.

As shown in Figure 13, the support structure for the clamp 139-141 is provided with a collar 133 adapted to slidably receive the support member 131 shown in Figure 12. This collar is provided with a thumb screw 142 for locking it in adjusted positions along the member 131. On the side opposite the slide collar 133 the shaft 134 carries a bolt and nut assembly 136 and is provided with opposed washers 135 arranged to hold the spirally wound portion 137 of the clamping means 140 in place on the shaft 134. The arranged portion 137 provides a spring mounting which normally urges the two fingers 138 and 140 to close their clamping plates 139 and 141 as shown by the full lines of Figure 12. The tongs may be opened to the dotted position of Figure 12 by applying squeezing pressure on the portions 138 and 140 against the resiliency of the coiled portion 137. It will be noted that the telescopic support means of Figures 12 and 13 is given the designation C' in Figure 12 to show that it may be substituted for the support means C of other figures. This provides a simple form of clamping device for sleeves and cuffs and other means. It will be noted that the tongs are rotatable about the bolt and nut assembly 136 against the resiliency of the spring portion 137.

In Figure 14 I have shown a simple form of a sleeve spreader for creasing a device which may take the place of or be used with the clamping device of Figure 12. It will be noted that the spring end portion 155 will be mounted in the same manner as the spring portion 137 of the other clamp. Further, in the clamp of Figure 14 the spring portion tends to urge its spreader plates 159 to an outward rather than an inward position with respect to each other and as opposed by a squeezing action on the handles 157. The end portions 158 of the side wire members 156 are secured as by welding to the spreader plates 159 and a pin 160 is mounted on each spreader plate to receive a tension spring 161 having opposing abutment ends 161a and 161b.

In Figure 15 I have shown somewhat diagrammatical-

ly an assembly which may be used with a fabric steamer bag whose sleeves are to be inflated and have closing means such as 149, 150 at their ends which carry a wire linkage 147. It is very important to have the arms of a garment under some tension during the steaming operation and in the proper relationship with respect to its other portions. Figure 15 thus shows a simple type of device that may be used with the adjustable telescopic support rods of either Figure 3 or Figure 12 for the purpose outlined. In this connection a slide sleeve or collar 145 having a thumb screw 142 for securing it in position on the telescopic member 131 also has a hook portion 146 to latch through a loop of the linkage 147.

In Figures 9, 10 and 11 I have illustrated a flap presser and clamping unit generally indicated as F in Figure 1A. Such a unit may be pivotally or hingedly mounted at its lower end to project upwardly from the rim and flange assembly 20, see the box hinge means 177 of Figure 1A which is shown secured to the wheel port 25. This clamp has a strap metal slide member 165 extending therealong and provided with a lower stop 167 and an upper stop 168 for slide portions 166a of a slide 166. In this way the full clamping assembly may be moved vertically with respect to the member 165. The arrangement is maintained in a suitably adjusted relationship by a spring clip 164 which is secured to a bag presser plate 169 having fabric ribbing 169a along its opposite sides.

A presser plate 175 having a reinforcing ribbing 174 and a mount piece 172 is pivotally secured by a bolt and nut assembly 173 to a back channel member 171. The back channel member 171 is pivotally mounted at 170 to the member 166 for swinging movement with respect thereto as opposed by the normal tendency of opposed tension springs 162 which are connected between such members. A handle member 176a provided with a hand grasp 176 is pivotally mounted on the channel member 171 and projects through an opening in the web portion of that member. The inner end of the member 176a slidably engages the adjacent surface of the member 166 for the purpose of controlling the relative positions of the pressure plates 175 and 169. As the hand grasp 176 is moved upwardly the opposite end of the member 176a moves downwardly along the surface of the member 166 and finally moves out of contact with that member, thus permitting the plate 175 to move into contact with the ribbing 169a on the plate 169.

In Figures 21 to 27, inclusive, I have illustrated three forms of collar-forming adaptors. I have shown one form in Figures 21 to 23, a second form in Figures 24 and 25 and a third form in Figures 26 and 27. In these figures the holes or perforations or ports in the presser plate member 33 have been omitted for simplicity. Referring again to Figure 18, an assembly such as shown in Figure 1 has a back opening 33b, see Figure 18, within which is adapted to fit a suitable collar shaping member such as 180 of Figures 21 to 23. The back face of the cap portion 32 has a projecting alignment pin 31 located below the opening 33b. Each of the adaptable collar shapers such as 180, 184 and 190, has a centrally slotted back plate member that is adapted to fit over the alignment screw 131. As applied particularly to the embodiment of Figure 22, the collar shaper 180 has a substantially planar back face portion which extends beyond the cap 32, and has curved-in ends 180a to form a support collar, for example, with relatively sharp corners from its back side. The front face of the cap part 32 serves to form the front portion of a collar. As shown particularly in Figure 23, the back face 181 of the collar shaper 180 slopes backwardly to form a shoulder and then slopes inwardly forwardly at 182 so that its bottom tab portions 182 serve as flexible clamps with the back portion 33a of the presser plate and with the projecting edge portion 32b of the cap part 32.

Ordinarily the fabric bag will have an opening therein along the slot or slit which is closed off by any one of the

75

adaptable collar shapers. The shaper 184 of Figures 24 and 25 has forward ear or wing portions 185 that are convexly curved from its back portion 186 to provide a more conventional type of collar shape. As shown particularly in Figure 25, the back face 186 latches under the edge 32d and slopes backwardly to an offset and into a forwardly sloped clamping spring tab portion 187.

In the embodiment of Figures 26 and 27, the shaper 190 is constructed with a back face 193 that forms a continuation of the curvature of the cap 32 to thus provide a substantially circular or rounded shape of collar. Like the other embodiments, this one also has a back face portion 191 which latches with the edge 32d of the cap, and spring tab portions 192 which latch with and are guided by the pin 31.

With reference to the steam flow coil 46 for the chest or breastplate 33, see Figures 17 and 18, this may be a copper pipe of about $\frac{3}{8}$ of an inch in diameter. The end portions of the coil 46 are connected to suitable steam inlet and outlet lines from the base unit A of the device, preferably by flexible rubber or plastic hose. This supplements the heating action of the steam and air flow from such base unit and enables the provision of relatively high temperature around the breastplate and collar portions of the garment. Where the collar portion is to be specially processed, I have also employed a suitable electrical resistance unit such as a calrod and mount it around the inside of the top closure wall portion 32c. Means may be also provided for controlling the amount of heat supplied by such a unit.

As shown particularly in Figure 1 of the drawings, a cone-shaped form 50, 51 may be employed for relatively large size garments such as overcoats, long dresses, etc., although the front plate 34 may be sufficient in some cases. As will appear, the cone-shaped form has an upper rim 53, a ported or mesh type intermediate portion 51 to deliver the steam and heated air to the skirt portion of a garment supported on the machine, and a solid bottom band portion 50. The connection between the portions 50 and 51 is shown reinforced by tabs 52. As will be apparent from a comparison with Figure 1, the cone-shaped member or form may be used or removed as desired and if used, rests upon the base rim 25 for movement therewith.

In Figures 28 to 31, inclusive, I have shown an improved form of permeable garment bag 200 which, as shown, is at its lower end mounted on the rim 25 of a base unit A; this bag may be of a permeable-flexible material, such as nylon cloth. This form has a back flap or bustle form 201 which defines a spacing 202 along the major portion of its vertical extent, but is connected at 203 to permit air and steam to pass from the main body into the flap and extend both of them substantially simultaneously. The form 200 is reinforced in its mounting by upwardly projecting aluminum rods 46' and 48, see particularly Figures 28 and 31. The side rods 46' incline vertically upwardly and have lower lugs 47 to latch with in slot mounts 25b that project outwardly on fingers 25a from the rim 25. In a like manner, a central slot mount 49 projects outwardly from the rim 25 to receive and support the central rod or rib 48 at its lower end.

In Figure 30 the broken line 207 indicates the position of the lining of an overcoat with relation to a form such as shown in Figure 29. The full line 209 indicates the position of the tail flap of a garment positioned on the machine with the tail flap extending over the bustle portion 201 of the form as shown in Figure 29 while the lining 207 of the garment is inserted in the slot 202 located between the main portion of the form 200 and the bustle portion 201.

As shown in Figure 28, the back portion of the form 200 may be adjusted for different size coats by means of slide fastener assemblies 205. By closing an assembly with its slider, a certain amount of cloth in the form is taken up to reduce the size and by opening the slider to

the position shown in Fig. 28, the maximum size of form is provided.

What I claim is:

1. An improved apparatus for finishing clothing which comprises, a flexible and permeable bag-like form, a base unit having a base rim rotatably mounted thereon, a central post rotatably mounted on said base unit and having a shoulder support, said form being mounted on said shoulder support and said base rim, support rods mounted on said base rim and projecting upwardly therefrom to reinforce said form, said form having a bustle portion along its back side with an open slot along a substantial vertical extent thereof to receive the lining of an article of clothing that is positioned on said form, said bustle portion being adapted to simultaneously receive a tail flap portion of the article, and slide fastener means along a portion of said form to increase and decrease its size.

2. In a garment pressing apparatus a base unit; a steam supply unit mounted on said base unit and positioned to deliver steam upwardly above said base unit; a hollow conical garment-positioning unit mounted on, axially aligned with an extending above said base unit and encircling said steam supply unit; a support column mounted on and extending vertically above said base unit and axially aligned with said garment-positioning unit; a shoulder support mounted on said column above and spaced from said garment-positioning unit; a shoulder expander assembly mounted on said column below said shoulder support unit and above said positioning unit and including shoulder-engaging members movable into and out of contact with the shoulders of a garment supported on said shoulder support; a pressing and clamping assembly pivotally mounted on said base unit and extending upwardly therefrom and movable toward and away from said garment-positioning unit; and a garment-tensioning unit mounted on said assembly and movable therewith toward and away from said positioning unit and longitudinally thereof.

3. A garment finishing machine including an open top hollow base member; a hollow conical foraminous intermediate member mounted on and axially aligned with said base member; a vertically extending support column mounted on said base member and axially aligned therewith and with said intermediate member; an apertured breastplate mounted on said column above and spaced from said intermediate member; a clamping and pressing assembly pivotally mounted on and extending above said base member and movable about its pivot support to and from a position adjacent to and substantially parallel with the external surface of said intermediate member and into and out of contact with said breastplate; and means for delivering a flow of fluid into and through said intermediate member and along said breastplate and through apertures formed therein.

4. A garment finishing machine including an open top cylindrical base member; a garment support column mounted on and extending vertically above said member; a hollow garment positioning unit mounted on and aligned with said member and surrounding said column; a pressing and clamping assembly pivotally mounted on said member and movable about its pivotal support toward and away from said external surface of said unit; and a tension applying device mounted on and movable relatively to said assembly and therewith toward and away from the surface of said unit.

5. A garment finishing machine including an open top hollow base member; a hollow conical foraminous inter-

mediate member supported on and axially aligned with said base member; a vertically extending support column mounted on said base member and axially aligned therewith and with said intermediate member; a combination shoulder support and breastplate mounted on said column above said intermediate member; a clamping and pressing assembly pivotally mounted adjacent the lower edge of said intermediate member and movable about its pivotal support into and out of contact with said breastplate; and the external surface of said intermediate member; a tensioning device mounted on and movable longitudinally of and with said pressing assembly into and out of contact with the external surface of said intermediate member; and means for delivering a flow of fluid into and through said intermediate member and along said breastplate.

6. In combination in a garment pressing apparatus including a base unit; a base ring concentric with and secured to said unit; a vertically extending post centrally located relatively to and secured to said ring; a shoulder support mounted on said post and spaced from said ring; a flexible, permeable fabric bag-like form draped on said support with the lower edge thereof secured to said ring; a bag-like bustle portion extending upwardly from the lower edge of said form, with the interior thereof in open communication with the interior of said form; and means extending upwardly into said form for delivering inflating fluid into the interior of said form.

7. A garment finishing machine including an open top base unit; a hollow conical intermediate garment positioning unit mounted on and axially aligned with and movable relatively to said base unit; a vertically extending support column mounted on said base unit and extending upwardly through said intermediate unit; a combined shoulder support and perforated breast plate mounted on said column above said intermediate unit; a heating coil in contact with the rear face of said breast plate; a pressing and clamping assembly pivotally mounted on said base unit extending upwardly along said intermediate unit and movable about its pivot point toward and away from said intermediate unit; and a garment tensioning device mounted on and movable with and longitudinally of said pressing and clamping assembly.
